Primary Examiner — Ian Simmons*Assistant Examiner* — Shannon Morgan*(74) Attorney, Agent, or Firm* — Leason Ellis LLP(57) **CLAIM**

The ornamental design for a swaddle blanket, as shown and described.

DESCRIPTION

FIG. 1 is a front elevation view of a swaddle blanket shown in an open position showing our design;

FIG. 2 is a front elevational view shown in a partially open position thereof;

FIG. 3 is a front elevational view shown in a partially open position thereof;

FIG. 4 is a front elevational view shown in a closed position thereof;

FIG. 5 is a rear elevational view thereof;

FIG. 6 is a left side elevational view thereof;

FIG. 7 is a right side elevational view thereof; and,

FIG. 8 is a top plan view thereof.

The broken lines showing fastening members, front seams, and infant in FIGS. 1-8 of the swaddle blanket are for the purpose of illustrating environment, and form no part of the claimed design.
